UNITED STATES PATENT OFFICE.

EDSON L. BEARDSLEY, OF COLUMBUS, OHIO.

LIFTER.

1,241,488.

Specification of Letters Patent.

Patented Oct. 2, 1917.

Application filed September 21, 1916. Serial No. 121,498.

To all whom it may concern:

Be it known that I, EDSON L. BEARDSLEY, a citizen of the United States, residing at Columbus, in the county of Franklin and 5 State of Ohio, have invented certain new and useful Improvements in Lifters, of which the following is a specification.

This invention relates to lifters designed for use in assisting in removing the springs 10 encircling the valve stems of internal combustion engines. In grinding or replacing these internal combustion engine valves, it is necessary to first remove the spring normally seating the valve, from its operative 15 position and then removing the entire valve.

The main object of my invention, therefore, resides in a peculiar structure of yoke member arranged to bear at one end upon the valve head and encircling the valve stem 20 at its other end, together with means for causing an elevation of the yoke member to lift the same against the tension of the holding spring.

The preferred embodiment of my invention 25 is shown in the accompanying sheet of drawings, in which similar characters of reference designate corresponding parts, and in which:

Figure 1 shows my improved type of lifter 30 in partial side elevation and partial section in its operative position in connection with an internal combustion engine valve and stem, and,

Fig. 2 is a bottom view of the lower leg of 35 the yoke member.

In these drawings, I have diagrammatically represented an engine body portion by the reference numeral 1, this engine being provided with a valve comprising a head 2 and a stem 3. The lower end of the valve 40 is provided with a washer 4, which latter is held in position by means of the pin 5 passing through the valve stem, in order that the spring 6 encircling the stem may be operatively held in position. In removing the 45 valve, it is first necessary to remove the pin 5 which releases the operative connection between the spring 6 and the valve stem 3. After this pin has been removed, the stem 50 itself may also be removed.

It is the means for permitting the removal

of the pin 5, with which my invention is particularly concerned. This lifter comprises a substantially U-shaped yoke member 7 having a pair of legs 8 and 9. The leg 8 has 55 its end bifurcated, as is shown at 10, in order to embrace the valve stem and also span the pin 5. The other leg 9 pivotally carries at its outer end, as is shown at 11, a cam lever 12 whose hump 13 is arranged to bear 60 upon the upper surface of the valve head 2 in such manner that when the lever is moved from the position shown in full lines in Fig. 1, to the position shown in dotted lines, the entire yoke member will be elevated against 65 the tension of the spring. When in such position, the pin 5 may be very readily removed, inasmuch as the bifurcated end of the leg 8 engages the underside of the washer 4 and carries the same away from this pin. 70 After the pin has been removed, the cam lever 12 is moved back to the position shown in full lines and the entire lifter removed from its operative position. After this, the valve may be readily removed in the manner 75 which will be obvious.

From the foregoing description, taken in connection with the accompanying sheet of drawings, it will be apparent that I have provided a lifter of considerable utility and 80 one wherein the valve may be removed by a simple application of my improved tool.

What I claim, is:

A lifter for use in removing the spring holding pin of a valve stem comprising 85 a substantially U-shaped yoke member, one leg of said member being bifurcated to fit the valve stem beneath the spring encircling the same, the other leg of said member having its outer end bent down to lie adjacent 90 the top of the head of said stem, and a cam lever pivotally carried by said downwardly bent end and arranged so that its hump bears directly on the head of said stem for lifting said yoke member against the tension 95 of the valve spring.

In testimony whereof I affix my signature in presence of two witnesses.

EDSON L. BEARDSLEY.
